UNITED STATES PATENT OFFICE.

WILLIAM E. McDONELL, OF ROCHESTER, NEW YORK, ASSIGNOR TO E. KIRSTEIN SONS COMPANY, OF ROCHESTER, NEW YORK, A CORPORATION OF NEW YORK.

OPHTHALMIC MOUNTING.

1,264,411.

Specification of Letters Patent. Patented Apr. 30, 1918.

Application filed December 20, 1917. Serial No. 208,001.

To all whom it may concern:

Be it known that I, WILLIAM E. McDONELL, a citizen of the United States, and resident of Rochester, in the county of Monroe 5 and State of New York, have invented certain new and useful Improvements in Ophthalmic Mountings, of which the following is a specification.

The present invention relates to ophthalmic mountings and more particularly to the type having finger piece guard levers mounted to turn about upright axes on the support of the mounting, an object of this invention being to provide a construction in which 10 the guard levers carry keepers for coöperating with the support in order to detachably secure the guard levers to the support.

To this and other ends, the invention consists of certain parts and combinations of 20 parts, all of which will be hereinafter described, the novel features being pointed out in the appended claims.

In the drawings:—

Figure 1 is a plan view of a mounting 25 constructed in accordance with this invention, the keepers being in one piece with the guard levers;

Fig. 2 is a vertical section of the embodiment shown in Fig. 1;

Fig. 3 is an enlarged perspective view of 30 a portion of the mounting shown in Fig. 1;

Fig. 4 is an enlarged perspective of another embodiment of the invention in which the keeper is in the form of a screw;

Fig. 5 is a vertical section through the embodiment shown in Fig. 4;

Fig. 6 is an enlarged vertical section 40 through a mounting in which the keeper is in the form of a pivoted latch on the guard lever;

Fig. 7 is an enlarged perspective of the embodiment shown in Fig. 6;

Fig. 8 is an enlarged vertical section of 45 another embodiment in which the keeper is in the form of a latch on the guard lever engaging the pivot pin or post above the guard;

Fig. 9 is a detail plan view of the embodiment shown in Fig. 8, the dotted lines showing 50 the keeper, disengaged with the post;

Fig. 10 is an enlarged perspective view of the embodiment shown in Figs. 8 and 9;

Fig. 11 is a vertical section through another embodiment of the mounting in which

the latch is in the form of a slide on the 55 guard lever engaging the pivot post beneath the guard lever;

Fig. 12 is a plan view of the embodiment shown in Fig. 11; and

Fig. 13 is a perspective view of the latch 60 employed in Figs. 11 and 12.

Referring more particularly to the drawings, 1 indicates the lenses which are connected by a support comprising, in this instance, a bridging portion 2, lens-attaching 65 devices 3, and horizontal connecting portions 4. Operating preferably on the upper face of the connecting portions 4 are guard levers 5 which have forwardly extending finger pieces 6 and rearwardly extending portions carrying nose bearing members 7. Preferably, the guard levers are pivotally connected to the support by pivot pins 8, which may be anchored in any suitable manner to the support, as at 9, to 70 project upwardly from the support for engagement by bearing sleeves 10 on the upper faces of the guard levers. Coil springs 11 surround the bearing portions 10, and each has one of its ends secured at 12 to the 75 guard lever and its other end bearing at 13 on the support.

In the embodiment shown in Figs. 1 to 3, each of the guard levers has an integral tongue formed thereon, this tongue being 85 bent downwardly at 14 in front of the support for the lenses, and thence rearwardly at 15 to engage with the under side of the support, or that side of the support opposite the side on which the guard lever is 90 mounted. This tongue being made of thin stock is pliable and, while readily holding the guard lever to the support, may be bent so as to clear the under side of the support in order to permit the guard lever to be re- 95 moved.

In the embodiment shown in Figs. 4 and 5, the parts are substantially identical with those shown in Figs. 1 to 3, inclusive, except that the lever retaining means is different. In Figs. 4 and 5, the guard lever 5 has a screw 14^a passed through the finger piece portions 6 of the guard lever to engage in an undercut portion 15^a in the support for the lenses, the top of the undercut portion being engaged by the free end of the screw 14^a in order to prevent the removal of the guard lever from the mount- 100 105

ing. The undercut portion is of such a length that the movement of the guard lever about its axis is permitted.

In the embodiment shown in Figs. 6 and 5 7, the parts are substantially identical with those shown in Figs. 1 to 3, inclusive, except that the keeper is different, and is held in keeping position by the spring which positions the guard lever. The keeper 14^b, in 10 this instance, is in the form of a bell crank lever pivoted at 16 to the guard lever in rear of the pivot of the latter, and on the under side of such lever, one end 17 of the latch 14^b being extended into a recess 18 in 15 the rear face of the support for the lenses so as to retain the guard lever on the support. The recess 18 is of such a length as to permit the latch to swing with the guard lever while the upper wall of the recess is 20 engaged by the latch to prevent the withdrawal of the guard lever. The latch 14^b also has an arm 19 which is extended upwardly at one side of the guard lever and is provided with a bend 20 in which the end 25 12^b of the spring 11 is engaged. This spring tends to hold the end 17 of the latch in the recess 18, the portion 19 of the latch limiting the movement of such latch under the action of the spring by engaging the side of 30 the guard lever.

In the embodiment shown in Figs. 8, 9 and 10, the pivot post 8^c is extended above the bearing portion 10^c of the guard lever, and is provided with a surrounding groove 21. 35 The latch 14^c is preferably in the form of a substantially inverted U-shaped member, one arm of which is pivoted at 16^c to the upper face of the guard lever in front of the pivot, while the other arm has a hook 40 19^c for engagement with the side of the guard lever, when the recess of the notched central portion 22 of the latch or keeper is engaged within the recess 21 of the pivot post. The spring 11 has its end 12^c engaged 45 with the latch or keeper 14^c, and tends to hold the recessed portion 22 of the latch within the recess 21 of the pivot or post, the hooked portion 19^c coöperating with the guard lever to prevent undue movement of 50 the free end of the latch, and at the same time preventing the tension of the spring throwing the latch into binding engagement with the pivot post.

In the embodiment of the invention shown 55 in Figs. 11, 12 and 13, the pivot post 8^d has a surrounding recess between the guard bearing portion and the support for the lenses. The guard lever supports the keeper or latch which, in this instance, is mounted 60 to slide on the guard lever, being in the form of a plate 14^d having lugs 23 at one end thereof bending upwardly and over the plate and engaging the guard lever in front

of the pivot. The plate is notched at 24 in order to fit within and conform to the groove 65 of the pivot post 8^d. Beyond the notched plate is an arm 25 which is formed with a hooked extension 26 to lie in rear of the pivot of the guard lever. The spring 11 has its end 12^d engaged with the hook 26 in 70 such a manner that the spring tends to hold the latch within the undercut portion of the post, and thus retain the guard lever in position on the mounting.

In all embodiments of the invention, the 75 keeper for the guard lever is mounted directly upon the guard lever and is adjustable to engage the support for the lenses in a manner to retain the guard lever on the support. By mounting the keeper on the 80 guard lever, the assembling of the parts of the mounting is facilitated, and at the same time, should the guard lever or the keeper become broken or get out of order, it is unnecessary to throw the whole mounting 85 away, but the mounting may be repaired by a new guard lever. As the keeper is mounted on the guard lever, it is not so liable to be lost, as it would be if the keeper were separate from the guard lever and the support for the lenses. Furthermore, the keeper by being on the guard lever may be arranged in a more inconspicuous position.

What I claim as my invention and desire to secure by Letters Patent is:—

95

1. An ophthalmic mounting comprising a support for the lenses, a nose guard pivotally and detachably mounted on the support, a latch for securing the guard to the support, said latch being movably mounted on 100 the guard lever, and a spring for the guard holding the latch in latching position.

2. An ophthalmic mounting comprising a support for the lenses, a nose guard pivotally and detachably mounted on the support, 105 a latch for securing the guard to the support, pivotally mounted on the guard lever to one side of the axis of the lever and having a portion coöperating with the support to hold the guard lever to the support and 110 also having a portion to one side of its pivot to abut the guard lever when the latch is holding the guard lever on the support, and a spring for the guard lever acting on the latch to hold the latter in abutment with 115 the guard lever.

3. An ophthalmic mounting comprising a support for the lenses, a nose guard pivotally and detachably mounted on the support, and a latch for securing the guard to the 120 support mounted on the guard lever and movable into and out of connection with the support to secure and release the guard lever.

WILLIAM E. McDONELL.
